[57] CLAIM

The ornamental design for the full shield safety handle for ski pole, as shown and described.

DESCRIPTION

FIG. 1 is a perspective view of a full shield safety handle for ski pole showing my new design; FIG. 2 is a left side elevational view thereof; FIG. 3 is a right side elevational view thereof; FIG. 4 is a bottom plan view thereof; FIG. 5 is a top plan view thereof; FIG. 6 is a front end elevational view thereof; and FIG. 7 is a rear end elevational view thereof. The broken lines in FIG. 1 showing the ski pole and the hand of a user are for illustrative purposes only and form no part of the claimed design.
